Filed Jan. 16, 1967, Ser. No. 5,422

Term of patent 14 years

(Cl. D26—8)

FIG. 1 is a perspective view of an indicator light for printed-circuit boards, showing my new design.

FIG. 2 is an end view, as seen from the top of FIG. 1.

FIG. 3 is a side elevational view.

The face on the end opposite to the light lens is substantially plain and unornamented.

I claim:

The ornamental design for an indicator light for printed-circuit boards, substantially as shown and described.
